RAILWAY DUMP CAR.

APPLICATION FILED DEC. 9, 1907.

3 SHEETS—SHEET 3.

UNITED STATES PATENT OFFICE.

THOMAS R. McKNIGHT, OF AURORA, ILLINOIS, ASSIGNOR TO WESTERN WHEELED SCRAPER COMPANY, OF AURORA, ILLINOIS, A CORPORATION OF ILLINOIS.

RAILWAY DUMP-CAR.

No. 888,526.

Specification of Letters Patent.

Patented May 26, 1908.

Application filed December 9, 1907. Serial No. 405,742.

To all whom it may concern:

Be it known that I, THOMAS R. McKNIGHT, a citizen of the United States, residing at Aurora, in the county of Kane, State of Illinois, 5 have invented certain new and useful Improvements in Railway Dump-Cars, of which the following is a specification, reference being had to the accompanying drawings.

My invention relates to railway dump cars, 10 and particularly to cars whose load is discharged by the tilting of the car-body.

More particularly still, it relates to cars whose load is discharged from the side of the car when the car is tilted.

15 As is well-known, dump cars which are adapted to be used upon railroads are limited in their width to a practically standard width on account of the distance between the tracks or between the tracks and the siding, in order 20 that cars may not project so far that they cannot pass one another. For this reason, when the cars are tilted laterally to discharge the load, a portion of the discharged load is apt to spread back over the tracks and over 25 the rails.

It is the principal object of my invention to provide a car whose bottom shall be of the normal or standard width when in carrying position but which may be automatically extended when the car is tilted for dumping so as to form a practical extension of the bottom of the car and thus discharge the load in such a way that it will not be caused to slide or fall backwards over the rails.

30 To that end, my invention consists in supplying the discharging edge of the car with an extension so placed that when the car is in its carrying position the extension will not project laterally beyond the sides of the car 40 but which when the car is tilted for the purpose of dumping may be caused to project beyond the discharging edge and form an extension of the bottom of the car.

In the drawings:—Figure 1 is an end view 45 of the car. Fig. 2 is an end view of the body of the car in tilted or discharging position, showing the position of the various parts when tilted. Fig. 3 is a side view of the body of the car. Fig. 4 is a detail, being a bottom 50 view of a portion of the levers which cause the movement of the extended portion of the car. Fig. 5 is a detail of the end portion of one of the levers and the link connection between it and the extending shelf, partly cut

away. Fig. 6 is an enlarged detail, being an 55 isometric view of one of the arms to which the links connecting them with the swinging shelf are secured.

Referring to the drawings, 7 indicates the central longitudinal sill of the car on which 60 are mounted supports 8. 9 indicates the car-body from the bottom of which depend a number of pairs of lugs 10 which are pivotally connected by means of pins 11 with the upper ends of the supports 8, so that the 65 car-body may tilt to one side or the other thereon. The car-body is tilted by any well-known and approved devices, which, being no part of my present invention, are not shown and whose operation will be readily 70 understood. It is believed, therefore that no description of them is necessary.

12 indicates the sides of the car-body. 13 indicates arms which are pivotally connected with the sides 12 near their top edges, and 75 which are pivotally connected with each other at their inner ends by means of a link 14.

15 indicates arms which are pivotally mounted at their upper ends on pins 16 which are centrally located at the ends of the 80 car-body 9 and are located above the inner ends of the arms 13. The arms 15 extend diagonally downwards and outwards and are pivotally connected at their outer ends with the sides 12 near the bottom edges of said 85 sides.

17 indicates arms which are pivotally connected at their upper ends to suitable supports 18 at each end of the car. The arms 17 extend diagonally downward and outward 90 and are pivotally connected at their outer ends to links 19 which extend substantially vertically upward and are pivotally connected at their upper ends to the arms 13 at points intermediate the outer and the inner 95 ends of said arms 13.

The mechanism thus far above described forms no part of my present invention, and it is believed that from the above description its operation will be readily understood. 100 When the car-body is tilted to one side or the other, the operation of these various arms is such as to hold the side 12 which is on the upper side of the car in its original position against the side of the car, but to cause the 105 side 12 which is upon the downward side of the car to be lifted relatively to the said downward side of the car into the position shown

at the right-hand side of Fig. 2, permitting the load to be discharged from the side of the car. This is the mechanism that I prefer to use, but of course other mechanism might 5 be used to lift the side portion of the car-body on the downward side of the car relatively to the discharge edge of the car when the car-body is tilted.

20 indicates aprons which are pivotally 10 hung upon each side of the car upon its discharge edge, and, as is best shown in Figs. 1 and 2, the upper edge of the aprons and the under edge of the bottom 21 of the car-body are correspondingly beveled so that when the 15 aprons 20 normally stand in a vertical position the beveled edges may be brought together, as is shown in Fig. 1, to prevent excessive jarring or rocking. These aprons extend longitudinally the whole length of the 20 discharge edge of the car.

22 indicates supports which are mounted upon and secured to the central sill 7 of the car, and are of sufficient number to act as proper supports for the mechanism which 25 operates the aprons hereinafter described, and will vary in number, of course, with the length of the discharge edge of the car and of the aprons 20.

23 indicates arms which are pivotally 30 mounted at their inner ends upon the supports 22. The inner end of the right-hand bar 23 is pivoted to the left of the central line of the support 22 upon one side thereof, and the inner end of the left-hand bar 23 is pivoted to the right of the central line of the support 22 upon the other side thereof. The bars 23 extend outward and downward and are adapted in their normal position to rest with their under sides upon the center sill 7, and 35 are bifurcated as at 24, at their lower ends.

25 indicates pins which pass through the bifurcated portions 24 of the arms 23 at the lower ends thereof.

26 indicates links which are pivotally connected at their inner ends to the bifurcated 45 portions 24 of the arms 23 further away from the ends than are the pins 25, and, extending diagonally upwards and outwards, are pivotally connected at their outer ends to lugs 50 27 on the inner or under sides of the aprons 20.

The operation of these devices is as follows:—When the car is in its normal position, the lower sides of the arms 23 rest upon the top of the center sill 7, and their length 55 and the length of the links 26 are such that the aprons 20 are supported in a vertical position,—that is to say, at right angles to the bottom of the car,—so that they do not project beyond the lateral edges of the car. 60 When the car-body is tilted into the position shown in solid lines in Fig. 2, the upper apron being prevented from falling inwards by the coming together of the two beveled edges above described, the arms 23 and links 26 remain in their normal position with reference

to the car-body and are carried up with it so that the apron 20 remains in its original position. As the link 23, however, upon the left-hand side is prevented from descending further by its bearing upon the top of the center sill 7, the tilting of the car-body causes the apron 20 to turn upon its hinge and to be lifted with reference to the car-body into the position shown in solid lines upon the left-hand side of Fig. 2, forming an extension of 70 the bottom of the car which throws the matter dumped farther away than it would be thrown if the apron were not there, the top of the apron being brought into approximate alignment with the bottom of the car. When 75 the car is returned to its normal or carrying position, the apron 20 is restored to its normal position, and the side portion 12 also is closed upon the car. When the car is tilted into the other position, it will be readily understood that the apron upon the other side is operated, as is shown in dotted lines in Fig. 2. The aprons 20 therefore, form an auxiliary discharge board, which, in discharging position, becomes substantially an 80 extension of the bottom of the car and what 85 may be called an extension-piece.

The car-body and the aprons may be made of wood as represented in the drawings, or 90 may be made of sheets of steel, if desired. 95

What I claim as my invention and desire to secure by Letters Patent is:—

1. In a dump car, the combination with a 100 tiltable car-body, a side-board, and mechanism adapted to separate the side-board from the car-body on the down side of the car when said car-body is tilted, of an extension-piece located at the discharge edge of the car-body bottom and normally held in position in which it does not project beyond the 105 car-body, and mechanism operated by the tilting of the car-body to automatically project the extension-piece upon the discharge edge beyond such discharge edge and return the said extension-piece to its normal position when the car-body is brought back to normal carrying position.

2. In a dump-car, the combination with a 110 tiltable car-body, side boards, and mechanism adapted to separate the side board from the car-body upon the lower side of the car when the car-body is tilted, of aprons hinged to the bottom of the car-body on its discharge edges, and mechanism connected with said aprons adapted to hold the aprons in non-projecting position when the car is in its normal carrying position and by the tilting of the car-body to automatically swing the apron upon the discharge edge of the car into a position extending beyond the discharge edge 115 of the car-body.

3. In a dump-car, the combination with a center sill, a tiltable car-body mounted thereon, and aprons suspended along the discharge edges of the bottom of said car-body, 120

125 130

of arms pivotally connected at their inner ends to said sill and extending laterally outwards therefrom, links connecting the outer ends of said arms with said aprons and adapted when said car-body is in normal position to hold the aprons in a non-projecting position and when said car-body is tilted to

automatically lift said aprons to form extensions of the car-body bottom, substantially as described.

THOMAS R. McKNIGHT.
